ATTORNEY

UNITED STATES PATENT OFFICE.

JOHN A. BRILL, OF PHILADELPHIA, PENNSYLVANIA.

DESIGN FOR A CAR-SEAT PANEL.

SPECIFICATION forming part of Design No. 26,068, dated September 22, 1896.

Application filed February 26, 1896. Serial No. 580,909. Term of patent 14 years.

To all whom it may concern:

Be it known that I, JOHN A. BRILL, a citizen of the United States, residing at the city and county of Philadelphia, State of Pennsylvania, have invented and produced a new and original Design for Car-Seat Panels, of which the following is a specification.

The essential feature of my design resides in the configuration of the panel, substantially as shown in the accompanying drawings, in which—

Figure 1 is a front elevation, Fig. 2 a side elevation, Fig. 3 a plan view, and Fig. 4 a perspective view, of the exterior of the panel.

The panel 1 has a plane bottom edge 2, curved sides 3 in front elevation, curving inwardly as they approach the top and curving outwardly at the top, where the sides merge into outwardly-extending ears 4, curved at their ends exteriorly and curving inwardly from the top 5, as shown in Fig. 3, the top 5 being segmental between the ears. In side elevation, the side lines 3 are reverse curved, or ogee-shaped, which gives a downward curve and an inwardly-projecting appearance to the panel when viewed from the side or from the top, as seen in Figs. 2 and 3,

the shape being in the nature of an attenuated reverse curve. Extending inwardly from the lower edge of the panel is a plane flange 6, ³⁰ intermittent at 7, and from the inner surface of the panel project cylindrical lugs 8.

The edge of the panel is defined by the beading 9, extending entirely around the edge of the panel on the front. ³⁵

On the exterior of the panel, centrally and extending outwardly from said outer surface, is a rib 10, in which is formed an exterior groove 11, cross-pieces 12 and 13 at the top and bottom, respectively, the sides of the rib ⁴⁰ 10 being provided with grooves 13 and segmental grooves 14, Figs. 3 and 4, continuous with the grooves 13.

Having described my invention, I claim—

The design for a car-seat panel, substantially as herein shown and described. ⁴⁵

Signed at the city of Hot Springs, county of Madison, and State of North Carolina, this 12th day of January, 1896.

JOHN A. BRILL.
